UNITED STATES PATENT OFFICE.

WILLIAM GETHMAN, OF OKLAHOMA, OKLAHOMA.

SEALING DEVICE.

1,322,559.

Specification of Letters Patent. Patented Nov. 25, 1919.

Application filed February 25, 1919. Serial No. 279,101.

To all whom it may concern:

Be it known that I, WILLIAM GETHMAN, a citizen of the United States, residing at Oklahoma, in the county of Oklahoma, and State of Oklahoma, have invented a new and useful Sealing Device, of which the following is a specification.

My invention relates to sealing devices and more particularly to a paraffin sealing device for sealing food containers.

The primary object of the invention is to provide a device whereby the paraffin may be heated and applied to the containers with great facility.

15 A second object of the invention resides in the provision of a novel mechanism for controlling the flow of the molten paraffin.

Another object of the invention is to provide a paraffin applying device which is 20 simple in construction, consists of few parts that may be readily assembled and disassembled, which are unlikely to become inoperative, which is simple in operation, and which may be manufactured and sold at a 25 minimum cost.

Other objects and advantages will become apparent from the following specification and attached drawing, and the inventive features explicitly defined in the appended claims.

The invention consists of combinations, arrangement of parts, operations and general assembly which will be hereinafter described and illustrated.

35 In the drawings Figure 1 is a side elevation of a paraffin applying device constructed in accordance with my invention, parts being broken away to show the interior parts of the device, and,

40 Fig. 2 is a vertical sectional view taken on line 2—2 of Fig. 1.

Referring to the drawing wherein like characters of reference indicate like parts in all the views, the numeral 5 denotes a 45 container for containing the paraffin and having an opening 6 in the bottom thereof.

For the purpose of melting the paraffin in the container 5 burners 7 are mounted in close proximity to the container.

50 Extending vertically in the container 5 is a reciprocable needle valve 8 which is movable through a guide 9 in the container and the top wall of the container itself. This valve 8 normally closes the opening 6.

55 The upper end of the valve projects above

the container and is provided with an elongated opening 10. A coil spring 11 encircles the valve and bears against a washer 12 carried by the valve and normally projects the same into the outlet 6.

60

Longitudinally movable through the opening 10 is a bar 13 which moves along the top of the container and through a guide 14. An inclined groove 15 is formed in the upper face of the bar 13. A ball 16 is engaged in this groove and is held in place by a set screw 17 carried by the valve which bears against this ball 16. By adjusting the set screw 17, the tension of the spring 11 may be varied.

70

Mounted in bearings 18 on the container 5 is a disk 19 which is eccentrically connected with a link 20 that is pivotally connected with the bar 13. A handle 21 is attached to the disk 19, by means of which 75 the bar 13 is moved through the opening 10.

It will be seen that by rotating the disk 19 the bar 13 will be moved through the opening 10 in the valve 8 and this valve 80 moved against the tension of the coil spring 11 which allows the molten paraffin to pass through the opening 6.

This disclosure is merely for the purpose 85 of illustrating my idea and in no sense do I limit myself to the exact arrangement herein illustrated and described. To the contrary, the invention may be modified in many different respects and that my limits of modification are only governed by the 90 subjoined claims.

What is claimed is:—

1. In a sealing device, a receptacle for containing a liquid and provided with an outlet opening in its bottom, a valve guide 95 mounted in the receptacle at one side thereof, a reciprocable valve movable through the guide and normally closing the outlet opening in the bottom of the receptacle, the valve being provided with a slot in its upper end, a bar movable in the slot and provided with an inclined groove, an anti-friction member disposed in the groove and engaging the valve rod, means for retracting the bar to unseat the valve, and means for 100 seating the valve.

2. In a sealing device, a container having an outlet opening therein, a reciprocable valve mounted in the container having an elongated opening therein, a bar longitudi- 110

nally movable through the opening and having an inclined groove in its upper face, a ball positioned in the opening in the valve and resting in the inclined groove, means for moving the bar whereby to raise the valve, and a coil spring normally urging the valve to a closed position.

3. In a paraffin applying device, a receptacle having an outlet opening therein, a guide mounted in the receptacle, a needle valve reciprocable in the guide and extending through the top of the receptacle, an expansible spring urging the valve to a seated position, the valve being provided with an elongated opening, a longitudinally movable bar passing through the opening in the valve and having an inclined groove therein, a ball retained in the opening in the valve and resting in the groove, a disk mounted on the receptacle, a link eccentrically connected with the disk and operatively connected with the bar, and a handle carried by the disk.

4. In a device of the character described a receptacle having an outlet opening therein, a needle valve vertically movable in the receptacle and having an elongated opening therein, a set screw carried by the valve and extending within the opening, a bar longitudinally movable through the opening the valve having an inclined groove therein,

a ball resting in the groove and retained in place by the set screw, means for retracting the bar whereby the valve is unseated, and an expansible spring urging the valve to close the outlet.

5. In a sealing device, a receptacle for containing a liquid and provided with an outlet opening, a valve reciprocable in the receptacle and normally closing the opening, the valve being provided with a slot in its upper end, a bar movable through the slot and having an inclined groove in its upper face, an anti-friction member mounted in the groove, a set screw threaded in the upper end of the valve and bearing against the anti-friction member, a coil spring mounted in the valve and normally urging the same to a position to close the opening in the bottom of the receptacle, the set screw being adapted to vary the tension of the coil spring, and means for sliding the bar through the slot in the valve to unseat the valve.

In testimony that I claim the foregoing as my own, I have hereto affixed my signature in the presence of two witnesses.

WILLIAM GETHMAN.
